UNITED STATES PATENT OFFICE.

AUGUST HEINE, OF SILVER CREEK, NEW YORK.

GRAIN-SCOURER.

SPECIFICATION forming part of Letters Patent No. 397,720, dated February 12, 1889.

Application filed November 22, 1887. Serial No. 255,884. (No model.)

To all whom it may concern:

Be it known that I, AUGUST HEINE, of Silver Creek, in the county of Chautauqua and State of New York, have invented new and 5 useful Improvements in Grain-Scourers, of which the following is a specification:

This invention relates to that class of grain-scouring machines in which the kernels are freed from adhering impurities by the attrition of the kernels against each other and against metallic scouring-surfaces, and which are provided with an air-separator, whereby the impurities dislodged from the grain are discharged from the machine.

15 The object of my invention is to produce a machine of this character which has a large scouring-surface in a compact form, in which the grain is thoroughly cleaned without subjecting the same to a harsh and violent action, and in which the dislodged impurities are quickly removed from the grain.

My invention consists of the improvements which will be hereinafter fully set forth, and pointed out in the claims.

25 In the accompanying drawings, Figure 1 is a longitudinal section of my improved grain-scourer. Fig. 2 is a cross-section of the upper portion of the machine in line $x-x$, Fig. 1. Fig. 3 is a fragmentary perspective view of 30 the scouring-cylinders and elevating mechanism. Fig. 4 is a fragmentary cross-section showing a slightly-modified construction of the elevating mechanism.

Like letters of reference refer to like parts 35 in the several figures.

A represents the frame of the machine, and a the inclosing casing secured thereto.

b represents the horizontal driving-shaft, journaled in bearings b' b^2 , secured to the 40 frame A.

b^3 represents the driving-pulley secured to one end of the shaft b .

C represents the perforated scouring-cylinder, secured at its end to flanged heads D D', 45 arranged, respectively, at the feed and tail ends of the cylinder. The head D at the feed end of the cylinder is provided with a central feed-tube, d.

d' represents arms, which connect the head D with a hub, d^2 , secured to the shaft b . 50

The head D' at the tail end of the cylinder C is provided with elevating-ribs e, a deflecting hub or cone, e' , and a central discharge-tube, e^2 , in a well-known manner.

F represents a perforated drum arranged 55 within the cylinder C and of smaller diameter than the latter, so as to leave an annular space, f, between the cylinder C and the drum F. The latter is preferably composed of a series of bent or curved perforated plates, f', which are 60 secured at one end to corresponding ribs or flanges, f^2 , formed on the head D, and at their opposite ends to a corrugated ring, f^3 , secured to the elevating-ribs e of the tail-head D'. The perforated sections f' are slightly separated or set apart, so as to leave longitudinal 65 openings or slots g between the adjacent edges thereof.

H represents perforated elevating-buckets arranged in the space f opposite each section f', or nearly so, between the cylinder C and drum F, and secured at one end to flanges h of the head D and at their opposite ends to flanged arms h', formed on the ring f^3 of the tail-head D'. The plates f' of the inner drum, 75 F, are arranged with their concave sides outwardly facing the elevating-buckets, and the latter are preferably composed each of two straight perforated plates secured together in V shape, as represented in Fig. 2. 80

I represents a vertical suction-spout arranged at the feed end of the machine and connected at its lower end with a ring, i, which projects into the feed-tube d of the head D. 85

i' represents the feed-spout, which discharges the grain into the suction-spout I.

J is a vertical suction-spout arranged at the tail end of the machine and provided in its side with an opening, j, which receives the 90 discharge-tube e^2 of the tail-head D'.

K represents a suction-fan arranged on top of the frame A, near the tail end of the machine, and connected at one side with the suction-spout I by a horizontal air-trunk, k, 95 and at the other side with the suction-spout J.

l l' represent gates or valves arranged, respectively, in the air-spouts K and J, whereby the air-currents on opposite ends of the scouring-cylinder can be regulated, and *l²* represents a regulating-valve arranged near the lower open end of the suction-spout J.

m represents air-inlet openings formed between slats *m'*, which are secured to the upper portion of the frame A and form part of the inclosing-easing *a*.

N represents the trough-shaped lower portion of the casing *a*, arranged below the scouring-cylinder C, and *n* represents a screw-conveyer arranged in the lower portion of the casing. This conveyer is driven from the main shaft *b* by a drive-chain, *n'*, and the fan is driven from the conveyer-shaft by an endless belt, *n²*. The grain to be scoured is fed by the feed-spout *i'* into the air-spout I, where it meets the air-current, whereby the light impurities—such as dust, chaff, &c.—are carried upward toward the fan and discharged, while the grain and heavier particles descend through the air-current and are delivered into the interior of the drum F through the feed-tube *d*. The convex upper sides of the lower plates, *f'*, of the drum and the rotary movement of the drum cause the grain to slide over these plates and fall through the spaces *g* between the lower plates into the lower portion of the outer cylinder, C.

The grain is fed into the machine in such quantities that the space *f* between the lower portions of the cylinder C and drum F is kept well filled, so as to cause the elevating-buckets to take up a portion of the grain and distribute the same constantly over a large portion of the ascending side of the scouring-cylinder. The grain which lies between the buckets and the ascending sides of the scouring-cylinder and drum moves back by gravity and is scoured, while the grain contained in the buckets is carried upwardly and distributed over the outer concave sides of the upper scouring-sections of the inner drum and is partly carried over and discharged on the descending sides of the cylinder and drum in a thin spray. The descending grain is scoured by rubbing against the descending buckets, which latter also serve to deflect the grain toward the descending sides of the cylinder and drum. The seeds—such as cockle, &c.—and small or broken grain pass through the perforations of the scouring-cylinder and fall into the trough N, while the larger scoured grains are discharged into the air-trunk J by the discharge devices attached to the tail-head D'. The scoured grain which is discharged into the air-trunk J is again subjected to the action of an air-current, whereby any remaining impurities are separated and removed therefrom. The suction created by the fan causes the exterior air to enter the casing *a* through the openings *m* between the slats *m'*. This air passes into the scouring-cylinder C through

the perforations thereof. Part of the air which has entered the scouring-cylinder moves toward the tail end of the same and passes into the suction-spout J through the discharge-tube *e²*, while the rest of this air passes through the perforations and slots of the inner drum, F, and into the suction-spout I through the feed-tube *d*. These air-currents are distributed over the entire length of the scouring mechanism and remove the impurities as soon as they are dislodged from the grain, whereby the fine impurities are prevented from being smeared over the kernels and the perforations of the scouring-surfaces are kept open.

My improved machine can be run at a very slow speed and with little power, as the continual elevating and agitating of the grain on one side of the cylinders and the descending of the grain on the opposite side thereof distribute the same over the greater portion of the scouring-surface in thin layers and allow the air-currents to pass freely through the same in all parts of the scouring mechanism.

In the modified construction represented in Fig. 4 perforated elevating wings or plates are substituted for the buckets.

When the grain is subjected to the action of a smut-machine before it is fed to my improved grain-scourer, the air-trunk *k* may be omitted, and the grain may be spouted directly into the feed end of the scouring-cylinder without being first subjected to a preliminary air separation.

I claim as my invention—

1. In a grain-scourer, the combination, with the rotating perforated scouring-cylinder, of an internal perforated scouring-drum secured to said cylinder so as to rotate therewith, and provided with longitudinal openings extending the length of the drum, and elevators arranged in the space between the drum and the cylinder, substantially as set forth.

2. In a grain-scourer, the combination, with the rotating perforated scouring-cylinder, of an internal scouring-drum composed of perforated plates secured to opposite ends of said cylinder and separated by longitudinal openings, and perforated elevating-buckets arranged in the space between the drum and the cylinder, substantially as set forth.

3. In a grain-scourer, the combination, with the rotating perforated scouring-cylinder, of a perforated scouring-drum secured within the cylinder and rotating in the same direction and with the same speed as the cylinder, elevators arranged between the cylinder and the drum, and a suction-fan having its eye connected with the end of the scouring-cylinder, whereby the air is drawn inwardly through the perforations of the scouring-cylinder and through the space between said cylinder and the inner scouring-drum to the fan, substantially as set forth.

4. The combination, with the inclosing-casing provided with air-inlets, of a perforated rotating scouring-cylinder arranged in said casing, a perforated scouring-drum arranged
5 within said cylinder and rotating in the same direction and at the same speed as the cylinder, elevators arranged between the cylinder and drum, a suction-fan, and air-spouts con-

necting the fan with both ends of the scouring-cylinder, substantially as set forth. 10

Witness my hand this 15th day of November, 1887.

AUGUST HEINE.
